Primary Examiner — Selina Sikder*(74) Attorney, Agent, or Firm* — The Rapacke Law Group, PA.(57) **CLAIM**

The ornamental design for a sexual stimulation control box, as shown and described.

DESCRIPTION

FIG. 1 is a bottom perspective view of the sexual stimulation control box showing the new design;

FIG. 2 is a top plan view of the sexual stimulation control box thereof;

FIG. 3 is a bottom plan view of the sexual stimulation control box thereof;

FIG. 4 is a left side elevational view of the sexual stimulation control box thereof;

FIG. 5 is a right side elevational view of the sexual stimulation control box thereof;

FIG. 6 is a front elevational view of the sexual stimulation control box thereof; and,

FIG. 7 is a rear elevation view of the sexual stimulation control box thereof.

The broken lines shown in the drawings are for illustrative purposes only and forms no part of the claimed design.
